UNITED STATES PATENT OFFICE

150,200

DESIGN FOR A LINED OVERSHOE

Harry W. Boettge, Berlin, Wis., assignor to Berlin Tanning & Mfg. Co., Berlin, Wis., a corporation of Wisconsin

Application October 10, 1947, Serial No. 141,865

Term of patent 7 years

(Cl. D7—4)

To all whom it may concern:

Be it known that I, Harry W. Boettge, a citizen of the United States, residing at Berlin, in the county of Green Lake and State of Wisconsin, have invented a new, original, and ornamental Design for a Lined Overshoe, of which the following is a specification, reference being had to the accompanying drawing, forming part thereof.

In the drawing:

Fig. 1 is a front and side perspective view of a lined overshoe showing my new design, the opposite side presenting substantially the same appearance as the side shown; and

Fig. 2 is a rear view of the lined overshoe.

My design for a lined overshoe of the type shown is specifically characterized by the plain pointed free end tongue and the pointed rear end of the turned down cuff, both of which have

a plain trimming, as illustrated in both views of the drawing.

I claim:

The ornamental design for a lined overshoe, substantially as shown and described.

HARRY W. BOETTGE.
